CLAIM

The ornamental design for the playback device, as shown and described.

DESCRIPTION

FIG. 1 is a front elevational view of a first playback device showing a first embodiment of our new design.

FIG. 2 is a perspective view of FIG. 1.

FIG. 3 is a front elevational view of a second playback device showing the first embodiment of our design.

FIG. 4 is a perspective view of FIG. 3.

FIG. 5 is a perspective view of a third playback device showing the first embodiment of our design.

FIG. 6 is a top view of FIG. 5.

FIG. 7 is a perspective view of a fourth playback device showing the first embodiment of our design.

FIG. 8 is an enlarged scale front elevational view of FIG. 7.

FIG. 9 is a front elevational view of a fifth playback device showing a second embodiment of our new design.

FIG. 10 is a perspective view of FIG. 9.

FIG. 11 is a perspective view of the third playback device showing the second embodiment of our design.

FIG. 12 is a top view of FIG. 11.

FIG. 13 is a front elevational view of the first playback device showing the second embodiment of our design.

FIG. 14 is a perspective view of FIG. 11.

FIG. 15 is an enlarged scale perspective view showing the first embodiment of the design isolated from the playback device shown in FIGS. 1-8; and,

FIG. 16 is an enlarged scale perspective view showing the second embodiment of the design isolated from the playback device shown in FIGS. 9-14.

(Continued)

The broken lines depict portions of the playback device that form no part of the claimed design.
